UNITED STATES PATENT OFFICE.

WENZL KWASH, OF DES MOINES, IOWA.

ZIGZAG HIDE-CUTTING MACHINE.

1,369,286.

Specification of Letters Patent. Patented Feb. 22, 1921.

Application filed June 10, 1920. Serial No. 388,000.

To all whom it may concern:

Be it known that I, WENZL KWASH, a citizen of Bohemia, and a resident of Des Moines, in the county of Polk and State of Iowa, United States of America, have invented a certain new and useful Zigzag Hide-Cutting Machine, of which the following is a specification.

The object of my invention is to provide 10 a machine for cutting hides which have the hair thereon, on zig zag lines without cutting the hair.

More particularly it is my object to provide such a machine including coacting cutting members adapted to cut hides on zig 15 zag lines, and to provide means for mounting said members whereby they may be supported in a variety of different positions, which means is adapted to support one or 20 more sets of said cutting members, and adapted to be adjusted for the ready and easy removal or interchange of the cutting members.

With these and other objects in view, my 25 invention consists in the construction, arrangement and combination of the various parts of the device, whereby the objects contemplated are attained, as hereinafter more fully set forth, pointed out in my claims, 30 and illustrated in the accompanying drawings, in which:

Figure 1 shows a front elevation of a zig 35 zag hide cutting machine embodying my invention.

Fig. 2 shows a vertical sectional view taken on the line 2—2 of Fig. 1.

Fig. 3 shows a detail sectional view taken on the line 3—3 of Fig. 1.

Fig. 4 shows a front elevation of one of 40 the cutting knives or die members.

Fig. 5 shows an end elevation of the machine.

Fig. 6 shows a plan view of the machine.

Fig. 7 shows a detail sectional view taken 45 on the line 7—7 of Fig. 1; and

Fig. 8 shows a front elevation of the coacting cutting members or dies, the upper cutting member being of slightly different form from that shown in Fig. 4.

In the drawings herewith, which illustrate a form in which my invention may be embodied, I have used the reference numeral 10 to indicate a base, in which is mounted the lower end of a hollow upright 50

11. A portion of the upright 11 is cut away,

as at 12 (Fig. 1) leaving a recess, and in such recess is mounted a motor 13. Above the recess 12 are opposite recesses 15 and 16 in the upright 11.

Extending through the walls of the upright 11, opposite the recesses 15 and 16, are spindles 17 and 18. The ends of the spindles 17 and 18 are mounted in vertically elongated slots 19, shown in Fig. 2.

Secured to the spindles 17 and 18 are bearings 20 and 21, through which extend shafts 22 and 23. On the left-hand ends of the shafts 22 and 23, as shown in Fig. 1, are pinions 24 and 25, which mesh with each other when the upper shaft is in its lowered 65 horizontal position, as illustrated, for instance, in Fig. 1. The shaft 22 projects beyond the pinion 24, and has thereon a sprocket 26 in line with a sprocket 27 on the motor shaft. On the sprockets 26 and 70 27 is a chain 28, by means of which power is transmitted from the motor shaft to the shaft 22.

Pivoted in the lower portion of the member 11 is a brace 29, which extends upwardly 80 and laterally to the right, as shown in Fig. 1. The brace 29 extends to a point to the left of the pivot 30 of said brace, and is connected with an expansion spring 31 which tends to hold the brace in its raised 85 position, but to permit the brace to be lowered against the pressure of the spring.

On the outer upper end of the brace 29 is formed a socket 32, in which are received lower and upper bearing members 33 and 34. 90 The upper bearing member 34 is fastened in position by means of a cotter pin 35, which is readily removable for removing the upper members and permitting the release of the outer end of the shaft 22, which, when 95 the machine is assembled, is received in the bearings 33 and 34.

Pivotal mounted on the opposite sides of the upright member 11 are brackets 36 and 36^a, which support a table 37 having a notch 100 37^a to receive the roller 47. On the outer upper portion of the brace 29 are brackets 38 for supporting the right-hand end of said table, which projects beyond the shaft 22.

It will be seen that the table may be swung 105 upwardly and downwardly with a pivotal movement with the brace 29. The edges of the table adjacent to the cutters hereinafter mentioned, are beveled as at 39.

Pivotal mounted in the upper portion 110

of the upright 11 is a supporting brace 30, which has one end projecting beyond the pivot 41 and connected with a spring 42 shown in Fig. 1. The brace 40 extends downwardly and laterally, as shown in Fig. 1, and has at its outer end a socket 43 in which are received upper and lower bearing members 44 and 45. The lower bearing 45 is held in position by means of a cotter pin 46, which is readily removable.

The outer end of the shaft 23 is received between the bearings 44 and 45. On the shafts 22 and 23 are rollers 47 and 48, in which are longitudinal grooves 49. The grooves 49 of each roller are preferably arranged diametrically opposite to each other, as shown in Fig. 3.

Connected with the end of the brace 40 on the left-hand side of the pivot 41, is a cable or the like 50, extending downwardly in the upright 11 to a foot lever 51 pivoted at 52 on the upright. The operator, by pressing on the lever 51 with his foot, may raise the supporting brace 40 and thereby raise the right-hand end of the shaft 23. It will be seen that the shaft 23 may be raised on account of the fact that the slot 19 is elongated.

On the rollers 47 and 48 are mounted cutting devices, a pair of which are shown in Fig. 3. In Fig. 8 I have shown the cutting devices in front elevation. The lower cutting device has a hub 53, on which is the hollow annular die member 54 forming the female element of the cutting die, provided with the connected zig zag grooves 55. The upper cutting member has a similar hub 56 and a die member 57 having the zig zag cutting blade or element 58 forming a continuous cutting blade. The cutting edges of the blade 58 are curved, as at 59, as illustrated in Fig. 8, from side to side, so that the sections of the cutting blade 58 at the connected portions thereof, as at 60, project farther from the roller 48 than do the central portions of the respective sections of said cutting blade. The thickness of the blade 59 is less than the width of the groove 55 to avoid cutting with a shearing cut. The hubs of the cutting members are provided with internal ribs or splines 61, which slide in the grooves 49.

This particular feature of the construction of my cutting device is important, for the reason that it is desirable to cut the leather but not to cut the fur, and where a shearing cut is employed the fur or hair would be cut.

In order to hold the hide taut between the cutting members, to permit the hide to be cut neatly without the employment of a shearing action, I have provided the following means:

On each roller I mount a gripping roller 62, which is slidably placed on the roller 48 or 47, as the case may be. The respective

gripping rollers 62 on the roller 48 register with the respective rollers 62 on the roller 47, so that the hide may be gripped between the gripping rollers on the respective rollers 47 and 48, for holding it taut during the cutting operation. The rollers 62 are provided with pins or the like 63, which project into the grooves 49 for holding the gripping rollers against rotation.

Two sets of cutting devices and gripping rollers may be mounted on the rollers 47 and 48, if desired, so that two cuts may be made on a hide at one time, where that is desirable.

In Fig. 4 I have shown a slightly modified form of the male cutting member, in which the cutting blade sections are arranged in slightly different manner than that shown in Fig. 8. The cutting member shown in Fig. 4 is indicated by the reference character 64.

In the practical use of my improved machine, the machine is assembled in the manner heretofore described. The gripping rollers and cutting members may be placed on the rollers 47 and 48, and adjusted thereon without difficulty. It will be noted that the brace 29 may be lowered at its outer end against the pressure of the spring 31, and that the table members 37 and 37^a will swing downwardly with the brace 29. The cotter pin 35 may be removed from the brace 29 and the bearing member 34 before the brace is lowered, and it is obvious that when the brace is lowered the end of the shaft 22 will be accessible for mounting the gripping rollers and the cutter members thereon. The brace 29 may then be raised, and the upper bearing member 34 replaced in position.

For placing the gripping rollers and the cutter member on the upper roller 48, the operator may put his foot on the lever 51 for raising the outer end of the roller 48, whereupon the cotter pin 46 may be removed and the bearing 45 taken out, after which the shaft 23 may be lowered slightly for making it possible to place on it the gripping rollers and the cutter member.

After the gripping rollers and cutting members have been assembled, the shaft 23 may be placed in proper position with relation to the bearing 44, and the bearing 45 replaced, as shown in Fig. 7. The roller 48 is then lowered into its horizontal position, and the machine is ready for use.

In cutting a hide 65, the hide may be placed on the table member 37 and shoved between the gripping rollers and the cutting members, whereupon it will be cut on a zig zag line. The hide is ordinarily cut with the hair down, and the hide itself will be cleanly cut but the hair will not be cut. It is necessary in cutting a hide, ordinarily to cut on irregular lines in order that the seam may not appear when two sections of

hide are sewed together along their cut edges. It is also necessary that the hide be cut without cutting the hair, and the difficulty of making a machine for the purpose of cutting hides in this manner will be obvious in view of those facts.

My machine is of simple construction, and will not easily get out of order. The cutter members may be adjusted on the rollers 47 10 and 48, for effecting cutting on the desired lines. With a machine of this kind the expense of cutting a hide will be very materially reduced.

Some changes may be made in the construction and arrangement of the parts of my improved zig zag hide cutting machine without departing from the real spirit and purpose of my invention, and it is my intention to cover by my claims any modified 20 forms of structure or use of mechanical equivalents which may be reasonably included within their scope.

I claim as my invention:

1. In a hide cutting machine, a pair of 25 shafts, coacting cutting members thereon, comprising a member having a zig zag groove and a member having a zig zag knife, the width of the groove being greater than the thickness of the knife, and means on the 30 opposite sides of each cutting member for gripping and engaging a hide for holding it taut.

2. In a device of the class described for cutting hairy hides, a support, a pair of 35 shafts mounted thereon, cutting devices supported on said shafts, said cutting devices being arranged to cut hides on zig zag lines, and having coacting cutting members or dies provided respectively with an irregular 40 groove and an irregular knife, substantially as shown, and gripping rollers supported on said shafts on opposite sides of said cutting knife, for engaging a hide and holding it taut during the cutting operation.

45 3. In a device of the class described, a support, a pair of shafts mounted thereon, cutting devices supported on said shafts, said cutting devices being arranged to cut hides on zig zag lines, and having coacting cutting 50 members or dies provided respectively with an irregular groove and an irregular knife, substantially as shown, said groove being of greater width than the thickness of said knife, and means for holding a hide taut 55 during the cutting operation.

4. In a device of the class described, an upright, a shaft supported thereon near one end of said shaft, for rotation, a roller on said shaft, an adjustable support for the 60 other end of said shaft, a second shaft mounted on said upright near one end of said shaft, an adjustable support for the other end of said second shaft, a roller on said second shaft, coacting cutting devices mounted 65 on said rollers for cutting hides on irregular

lines, and gripping rollers on each of said first-named rollers, on opposite sides of the cutting devices, for gripping and holding a hide taut.

5. In a device of the class described, an 70 upright, a shaft supported thereon near one end of said shaft, for rotation, a roller on said shaft, an adjustable support for the other end of said shaft, a second shaft mounted on said upright near one end of said shaft, an adjustable support for the other end of said second shaft, a roller on said second shaft, coacting cutting devices mounted on said rollers for cutting hides on irregular 75 lines, and gripping rollers on each of said first-named rollers, on opposite sides of the cutting devices, for gripping and holding a hide taut, said cutting devices and gripping rollers being slidably but non-rotatably mounted on said first-named rollers.

6. In a device of the class described, an 80 upright, a shaft supported thereon near one end of said shaft, for rotation, a roller on said shaft, an adjustable support for the other end of said shaft, a second shaft 85 mounted on said upright near one end of said shaft, an adjustable support for the other end of said second shaft, a roller on said second shaft, coacting cutting devices mounted on said rollers for cutting hides on irregular 90 lines, gripping rollers on each of said first-named rollers, on opposite sides of the cutting devices, for gripping and holding a hide taut, said cutting devices and gripping rollers being slidably but non-rotatably mounted on said first-named rollers.

95 100

7. In a device of the class described, an upright, a shaft supported thereon near one

105

end of said shaft, for rotation, a roller on

said shaft, an adjustable support for the

other end of said shaft, a second shaft

mounted on said upright near one end of said

shaft, an adjustable support for the other

end of said second shaft, a roller on said sec-

ond shaft, coacting cutting devices mounted

on said rollers for cutting hides on irregular

lines, and gripping rollers on each of said

first-named rollers, on opposite sides of the

cutting devices, for gripping and holding a

hide taut, a motor on said upright, means for

imparting movement from said motor to one

of said shafts, and gearing devices for con-

nnecting said shafts.

110 105

7. In a device of the class described, an upright, a shaft supported thereon near one

end of said shaft, for rotation, a roller on

said shaft, an adjustable support for the

other end of said shaft, a second shaft

mounted on said upright near one end of said

shaft, an adjustable support for the other

end of said second shaft, a roller on said sec-

ond shaft, coacting cutting devices mounted

on said rollers for cutting hides on irregular

lines, and gripping rollers on each of said

first-named rollers, on opposite sides of the

cutting devices, for gripping and holding a

hide taut, one of said shafts being pivotally

and slidably supported on said upright.

115 120

8. In a device of the class described, an upright, a shaft mounted near one end of

said upright and projecting away from the

upright, a second shaft pivotally and slid-

ably mounted on said upright near one end

of the second shaft, gearing devices for con-

nnecting said shafts, means for imparting mo-

tion to one of said shafts, a pivoted support

mounted on said uprights and connected

with the outer end of said second shaft, a

foot lever operatively connected with said

last described support, cutting devices sup-

ported on the respective shafts, and gripping

130

rollers on opposite sides of the cutting devices, for holding a hide taut during the cutting process.

9. In a machine of the class described, 5 means for holding a hide with the fur thereon taut, cutting devices interposed between said means and comprising a member pro-

vided with a groove and a coacting cutting member adapted to enter said groove spaced from the edges thereof for cutting a hide 10 without cutting the fur thereon.

Des Moines, Iowa, May 28, 1920.

WENZL KWASH
